UNITED STATES PATENT OFFICE.

CHARLES M. LEECH, OF CLEVELAND, OHIO; CHARLES E. KINDELL ADMINISTRATOR OF
SAID CHARLES M. LEECH, DECEASED.

INTERNAL-COMBUSTION ENGINE.

1,407,468.

Specification of Letters Patent. Patented Feb. 21, 1922.

Application filed April 1, 1920. Serial No. 370,508.

To all whom it may concern:

Be it known that I, CHARLES M. LEECH, a citizen of the United States, residing at Cleveland, in the county of Cuyahoga and 5 State of Ohio, have invented a certain new and useful Improvement in Internal-Combustion Engines, of which the following is a full, clear, and exact description.

This invention relates to internal combustion engines of the two-cycle type, and has particular reference to engines constructed along the lines of, and embodying certain features of engines disclosed in several prior patents granted to me, including 10 Patents No. 1,138,876, May 11, 1915; No. 1,068,595, July 25, 1913; No. 914,292, March 2, 1909; No. 1,082,494, May 9, 1916; and No. 1,099,065, June 2, 1914.

The principal object of the invention is to 15 provide certain improvements which render a two-cycle engine, particularly of the single cylinder type, more efficient and satisfactory in operation, the invention in certain respects having particular reference to a 20 single cylinder engine, though other features are adaptable for engines having more than one cylinder.

The invention pertains particularly to certain improvements in the construction of the 25 jacket by which the engine cylinder or cylinders are cooled by air; also to the manner of forming the cylinder, particularly the lower pumping portion by which mixture is more or less compressed and driven into the 30 working portion of the cylinder, the last mentioned feature having special utility for a single cylinder two-cycle engine, and it 35 pertains also to the manner of forming the piston. Additionally the invention may be 40 said to consist in certain novel details of construction and combinations and arrangements of parts which will be described in the specification and set forth in the appended claims.

45 In the accompanying sheets of drawings, wherein I have shown the preferred embodiment of a single cylinder, two-cycle engine constructed in accordance with the present invention, Fig. 1 is a vertical sectional view 50 of an engine equipped with a preferred form of my invention; Fig. 2 is another vertical sectional view taken at substantially right angles to the section of Fig. 1; Fig. 3 is a side elevation of the engine; Fig. 4 is a top 55 plan view, and Fig. 5 is a horizontal sec-

tional view substantially along the line 5—5 of Fig. 1.

In the drawings, 10 represents a crank-case and 11 the main cylinder casting in the upper working portion of which is adapted 60 to reciprocate a piston 12 connected by a connecting rod 13 to a crank-shaft 14. It will be observed that the crank-case is composed of a cylindrical body portion 10^a with two circular end plates 10^b bolted to the 65 ends of the body portion and having bearings 10^c for the crank-shaft 14. At the top of the body portion of the crank-case there is an integral tubular extension 15, whose axis is coincident with the axis of the piston, and which forms the inner wall of a pumping cylinder as will be explained presently. It will be observed that the connecting rod extends downward through this tubular extension 15 to the crank-shaft. 75

The cylinder casting 11 has an upper working portion 11^a in which the upper part of the piston slides, and it has an enlarged lower portion 11^b which is concentric with respect to the tubular extension 15 of the 80 crank-case and forms the outer wall of the pumping cylinder. It will be observed that the tubular extension 15 of the crank-case is somewhat smaller in external diameter than the internal diameter of the working 85 portion 11^a of the cylinder casting, and that this tubular extension 15 terminates just below the shoulder formed at the junction of the working and pumping portions of the cylinder casting. 90

The piston 12 is composed of a head 12^a and a sleeve-like extension 12^b, these parts being separately formed, and being fastened together by screwing the head into the upper part of the sleeve 12^b. The head 95 12^a has a boss 12^c to which the upper end of the connecting rod 13 is pinned, this boss being located below the annular threaded part of the head which is screwed into the sleeve part 12^b of the piston so that it is 100 possible to readily machine the boss to accommodate the pin which fastens the connecting rod to the piston. It will be observed that when the piston is at the bottom of its stroke the boss 12^c extends down into 105 the tubular extension 15 of the crank-case so that the ordinary method of connecting a piston and connecting rod can not be utilized with this construction, it being therefore important from a production 110

standpoint that the head be separately formed from the sleeve of the piston for machining purposes.

The sleeve 12^b of the piston engages the outer surface of the tubular extension 15 of the crank-case, and it engages also the working portion 11^a of the cylinder, the difference between the inner diameter of the working portion of the cylinder and the external diameter of the tubular extension 15 of the crank-case being equal substantially to the thickness of the sleeve 12^b of the piston. The upper part of the sleeve 12^b of the piston has a number of piston rings 16 engaging the working portion 11^a of the cylinder, the upper ring 16 being held in place by a peripheral flange of the head which extends over the extreme upper end of that portion of the sleeve 12^b to which the piston head is attached. Additionally the upper part of the crank-case extension 15 has a piston ring 17 which engages the inner wall of the piston sleeve 12^b. The lower part of the piston sleeve 12^b has a lateral extension constituting a secondary piston 12^d, this lateral extension or pumping piston having a piston ring 12^e engaging the pumping portion 11^b of the cylinder casting. As will subsequently appear, the lower part of the piston sleeve, i. e., the pumping portion, forms a double acting piston for the two-fold purpose of circulating or pumping air for cooling the upper part of the cylinder, and for the purpose of pumping mixture into the working portion of the cylinder.

Mixture is supplied to the engine independently of the crank-case, except the tubular extension 15 which serves as a part of the pumping cylinder for the mixture, through a rotary valve 18 which is preferably driven by the crank-shaft at one-half the speed of the latter, this valve being mounted to rotate in a ported sleeve 19 in a valve casing 20 formed at the lower part of the cylinder casting 11. This valve will have a suitable connection with the carbureter, and it has a pair of oppositely disposed ports 18^a, one of which at each revolution of the crank-shaft and on the up stroke of the piston admits mixture through a port 21 into the space beneath the pumping portion 12^d of the piston between the pumping portion 11^b of the cylinder and the tubular extension 15 of the crank-case. On the up stroke of the piston the pumping portion 12^d sucks a charge into the space just referred to, and on the down stroke the mixture is expelled from this chamber or cylinder through a port 22, in this case diametrically opposite from the inlet port 21, and from this port the mixture is driven through an upwardly extending passageway 23, at the top of which is a rotary throttle valve 24 which controls the admission of the mixture into the cylinder,

this throttle valve in this instance co-operating with a series of vertically disposed inlet ports 25 leading from the chamber of the throttle valve to the working portion of the cylinder as shown in several of my prior patents already referred to. These ports are uncovered by the piston at or about the bottom of the piston stroke, and at or about the same time the piston uncovers one or more exhaust ports 26 diametrically opposite from the throttle controlled inlet ports 25. The exhaust ports 26 communicate with an exhaust passageway 27 cored into the cylinder casting and leading downward to that part of the cylinder casting housing the rotary inlet valve 18 so that a certain amount of heat will be transmitted to the mixture before passing into the engine, and the exhaust is carried from the cylinder casting by an exhaust pipe 28 screwed into the casting just above the inlet valve 18.

It may be stated at this point that when the piston approaches the end of its upward stroke, air may be admitted through a port 29^a, which port is controlled by an auxiliary valve 30, likewise of the rotary type, which in this instance is connected by a rod 31 to the throttle valve 24 so as to work in unison therewith. In other words, when the engine is throttled down, this port will be practically or entirely closed, but when the throttle valve is opened to speed up the engine, this auxiliary air port is opened so as to allow more air to be admitted to the mixture. While the auxiliary air valve 30 is preferably connected to the throttle valve so as to work in unison therewith, nevertheless I contemplate having this valve operable by hand or otherwise independently of the throttle valve. This valve 30 is preferably in the form of a sleeve or hollow tube which for a single cylinder engine is open at one or both ends but for an engine of four or six cylinders the tube is preferably open between the cylinders as well as at its ends so as to give it ample capacity and provide for equal distribution of air to all the cylinders.

It will be understood, therefore, that on the up stroke of the piston a charge is sucked into the pumping portion of the cylinder, and on the down stroke this mixture is driven into the chamber or passageway 23, the inlet valve 18 being so timed that communication between the lower pumping portion of the cylinder and the inlet valve 18 is closed before the piston starts on its downward stroke. During the major portion of the downward stroke of the piston, the mixture is compressed in the lower pumping portion of the cylinder and in the chamber or passageway 23, and as soon as the piston uncovers the inlet ports 25, the mixture rushes into the working portion of the cylinder.

der, expelling the burnt gases resulting from the combustion of the previous charge in the cylinder.

Having explained the pumping function 5 of the pumping portion of the piston so far as it relates to the supply of mixture to the working portion of the cylinder, I will next explain the pumping function of this portion of the piston in so far as it relates to the 10 cooling of the cylinder. It will be observed that the working portion of the cylinder is surrounded by a jacket 29 which is secured by a nut 30^a to a tubular extension on the cylinder head at the top of the cylinder, this 15 jacket 29 surrounding external vertical fins 31 on the upper working portion of the cylinder and extending downward to a point just below the shoulder formed by the junction of the working and pumping portions 20 11^a and 11^b of the cylinder casting. This shoulder or lateral extension of the cylinder casting is provided with a series of air ports 32 located between the fins 31, these ports 32 communicating with the vertical spaces between 25 the fins enclosed by the jacket, and communicating with the pumping cylinder or chamber formed above the pumping portion 12^a of the cylinder and the sleeve 12^b of the piston. Additionally the jacket 29 is 30 provided just above the openings 32 in the cylinder casting with lateral ports or openings 33 which may be termed air intake openings, and at the top the jacket is provided with openings 34 which may be termed 35 air exhaust openings. The construction is such that on the down stroke of the piston air is sucked into the air pump cylinder, this being the stroke which drives the gas beneath the pumping portion of the piston 40 from the gas pump cylinder into the compression chamber 23, and finally into the working portion of the cylinder. On this down stroke of the piston cool air is sucked into the lateral ports or openings 33, and 45 some air is, of course, at the same time sucked into the upper openings 34. On the up stroke air is expelled by the pumping portion of the piston through the air pump cylinder, out through the openings 32, and 50 up along the wall of the working portion of the cylinder, and out through the upper openings 34 so that a maximum cooling action is obtained.

The engine above described is not only extremely efficient in operation, but the construction is simple, rendering it possible to produce the engine in quantities at low cost. I do not desire to be confined to the exact details shown, as changes may be made without departing from the spirit and scope of my invention in its broadest aspect.

Having described my invention, I claim:—

1. In an internal combustion engine of the

two cycle type, a crank case having a cylindrical extension, a cylinder having a working portion and a pumping portion, the pumping portion surrounding the crank case extension, a piston engaging the working portion of the cylinder and having a sleeve surrounding the extension of the crank case 65 and having a pumping portion adapted to reciprocate between the pumping portion of the cylinder and the crank case extension, ports in the pumping portion of the cylinder for the admission of mixture to the space 70 beneath the pumping portion of the piston and for the delivery of the mixture to the working portion of the cylinder, and an air port in the pumping portion of the cylinder 75 adapted to be uncovered by the pumping portion of the piston on the suction stroke thereof.

2. In an internal combustion engine of the two cycle type, a crank case having a cylindrical extension, a cylinder having a working portion and a pumping portion, the pumping portion surrounding the crank case extension, a piston engaging the working portion of the cylinder and having a sleeve 85 surrounding the extension of the crank case 90 and having a pumping portion adapted to reciprocate between the pumping portion of the cylinder and the crank case extension, ports in the pumping portion of the cylinder for the admission of mixture to the space 95 beneath the pumping portion of the piston and for the delivery of the mixture to the working portion of the cylinder, and a valve controlled air port in the pumping portion of the cylinder adapted to be uncovered by 100 the pumping portion of the piston upon the suction stroke thereof.

3. In an internal combustion engine of the two cycle type, a crank case having a cylindrical extension, a cylinder having a working portion and a pumping portion, the pumping portion surrounding the crank case extension, a piston engaging the working portion of the cylinder and having a sleeve surrounding the extension of the crank case 105 and having a pumping portion adapted to reciprocate between the pumping portion of the cylinder and the crank case extension, ports in the pumping portion of the cylinder for the admission of mixture to the space 110 beneath the pumping portion of the piston and for the delivery of the mixture to the working portion of the cylinder, and a throttle valve, an air valve coupled thereto and a port controlled by said air valve for 115 supplying air to the mixture on the pumping stroke of the pumping portion of the piston.

In testimony whereof, I hereunto affix my signature.

CHARLES M. LEECH.
